UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

SEWING AND TRIMMING MACHINE.

Application filed August 4, 1916. Serial No. 113,071.

To all whom it may concern:

Be it known that I, ALBERT H. DE VOE, a citizen of the United States, residing at Westfield, in the county of Union and State 5 of New Jersey, have invented certain new and useful Improvements in Sewing and Trimming Machines, of which the following is a specification, reference being had thereto in the accompanying drawings.

10 This invention relates more particularly to improvements in that class of sewing machines comprising stitch-forming and fabric-cutting or trimming devices operating in conjunction with a travelling work-holder, 15 and designed particularly for uniting the overlapped ends of long lengths of fabric in readiness for dyeing, singeing and bleaching operations thereon.

The invention has for its object to provide 20 improved means for controlling the operation of the stitch-forming and cutting mechanisms, for supporting the work in stretched condition and feeding the same to said mechanisms, to provide simple and effective cutting mechanism and means for 25 guiding the work thereto for cutting respectively the upper and under plies of the superposed fabrics, and for providing mechanism which is otherwise convenient to manipulate and effective in operation.

According to the present invention in its preferred embodiment, the stitch-forming mechanism comprises three laterally spaced needles and cooperating loop-takers adapted 30 for production of three lines of stitching across the overlapped ends of the strips of fabric to be united. The marginally superposed plies of fabric are secured adjacent the side edges upon impaling pins projecting 35 from the opposite faces of fabric-supporting and separating plates of a travelling work-holder connected by means of a belt running over a clutch-driven grooved pulley connection with the source of power. Means are 40 provided, including a common controlling or starting lever for coupling and uncoupling the stitch-forming mechanism with its actuating means and operating the clutch to connect and disconnect said grooved pulley and 45 its driving means, respectively. Through suitable connections, the same controlling lever is adapted to operate the presser-foot 50

lifting means and a tension-releasing device.

The cutting mechanism preferably comprises a pair of cutting elements for severing the upper ply of fabric including a reciprocating upper knife-blade cooperating with a fixed ledger-blade sustained by the machine bracket-arm, and a pair of cutting elements for cutting the lower ply of fabric 55 including a fixed ledger-blade sustained by the throat-plate and a reciprocating cutting element carried by a spring-lifted arm overhanging the throat-plate and actuated by a pressure member sustained from above the 60 throat-plate and operatively connected with the actuating means for the upper-ply trimming blade. The stitching, trimming and feeding devices are preferably sustained by a sewing machine head or frame mounted 65 upon a supporting plate or platform mounted for vertical adjustment upon a table having standards provided with bearing rollers which are lowered into operative position 70 with the floor to facilitate movement of the machine and raised from the floor for deposit of the standards thereon by means of a suitable toggle device.

The invention will be understood by reference to the accompanying drawings, in which Fig. 1 is a rear side elevation of a machine embodying the present invention, Fig. 2 a front end view and Fig. 3 a plan of the same. Fig. 4 is an enlarged side elevation of the forward part of 80 the machine, partly in section, and Fig. 5 is a sectional end view showing certain parts represented in Fig. 2. Fig. 6 is a perspective view of a part of the work-holder actuating mechanism. Figs. 7 and 8 represent 85 in end view and bottom plan, respectively, the starting or controlling lever and the tripping means therefor. Fig. 9 is a front end view of a portion of the bracket-arm head showing a part of the cutter-actuating 90 means. Fig. 10 is an elevation, partly in section, showing, upon a larger scale than Fig. 4, the spaced pairs of cooperating fabric-cutting elements, and Fig. 11 is a detail sectional view of a portion of the cutting 95 device for the lower ply of fabric. Fig. 12 is a sectional plan showing the cooperating elements of the upper-ply trimmer and accessories; and Fig. 13 is an enlarged sectional 100

front elevation representing some of the same parts. Fig. 14 is a perspective view of the movable element of the upper-ply trimmer. Figs. 15 and 16 are perspective views 5 representing the upper and lower faces, respectively, of the throat-plate. Fig. 17 is a perspective view of the movable member of the lower-ply trimmer and a portion of its carrier. Fig. 18 is a side elevation, partly 10 in section, of the starting or controlling lever.

As represented in the drawings, the table comprises end standards constructed with legs 1 connected in pairs by cross-members 15 2, said standards being braced by the tie-rods 3. The legs are provided in their upper ends with vertical sockets 4 in which are adjustably secured by set-screws 5 the plunger-pins 6 upon the upper ends of which is 20 secured by screws 7 tapped into the same the dished platform or base-plate 8.

Secured to the bottom of the base-plate is a depending hanger 9 in which is mounted the driving shaft 10 carrying the belt-wheel 25 11 embraced by the driving belt 12 from the source of power. As disclosed more fully in my application Serial No. 85,535, filed March 21, 1916, the shaft 10 has loosely mounted thereon a cone-pulley comprising the belt-wheel 13 and the connected grooved brake-wheel 14, and has fixed thereon the clutch-disk 15 adapted to be thrust into a lateral clutch-cavity formed in the brake-wheel by 30 means of the endwise movable plunger-pin 16 journaled in the hanger 9. Suitably fulcrumed upon the hanger is the spring-retracted operating lever 17 having a lateral arm 18 carrying the inclined cam-plate 19 adapted for engagement with the end of 35 the plunger-pin 16 for establishing driving connection between the shaft 10 and the belt-wheel 13.

The sewing machine frame is formed with the base 20 secured upon the platform 8 and 45 having rising therefrom the usual hollow standard 21 from which extends the tubular overhanging member 22 terminating in the head 23. Journaled within the head is the reciprocating needle-bar 24 provided with the needle-clamp 25 carrying the laterally spaced needles 26 cooperating with the loopers 27 operating beneath the throat-plate 28.

Upon the needle-bar is secured a collar 29 connected by means of the link 30 with a 55 crank-arm 31 fixed upon the forward end of the needle-actuating rock-shaft 32 which is operatively connected by suitable means with the main-shaft 33 journaled in the machine base and carrying the balance-wheel 34 which is formed with the belt-pulley 35 connected by means of the encircling belt 36 with the belt-wheel 13. The looper mechanism is or may be constructed and operated in accordance with my Patent No. 1,085,801, 60 of February 3, 1914.

The regular drop-feed mechanism is preferably constructed in accordance with my Patent No. 1,048,446, of July 27, 1915, and is constructed with a feed-dog 37 comprising the several serrated feeding elements passing through suitable apertures of the throat-plate and carried by the feed-bar 38 which is connected with the feed-rocker 39 operated by a connection with the main-shaft 33. 75

Opposed to and cooperating with the feed-dog 37 in its direct engagement with the work, for advancing it to space the stitches, is the presser-foot 40 having its shank secured to the presser-bar 41 journaled in the 80 bracket-arm head 23 and pressed downwardly by means of the spring 42. As represented more fully in my pending application Serial No. 48,594, filed September 2, 1915, the presser-bar has fixed thereon the thrust-block 43 adapted for engagement by the member 44 of a sliding collar carrying the roller-stud 45 and having a suitable connection with the lifting rock-lever 46 fulcrumed at 47 upon the overhanging frame 90 member 22. The finger-lever 48 having the fixed fulcrum 49 embraces within its cam recess 50 the roller-stud 45 and serves, in addition to its function as a lifting member, to move idly in the lifting movement of the 95 rock-lever 46 without effect upon the presser-foot or to lock the same in raised position under its momentum in passing from one to the opposite side of its fulcrum 49.

The tension device and its releasing 100 means are or may be constructed in accordance with my Patent No. 1,046,405, of July 13, 1915. It is shown comprising the supporting plate 51 sustained by the reciprocating plunger-pin 52 and carrying the tension-disks 53 normally pressed together by means of the springs 54 interposed between each outer tension disk and the thrust-nut 55 upon the respective tension-stud 56. Tension release pins 57 extending axially 110 through the studs 56 and connected with the respective springs 54 are adapted to engage the fixed thrust-plate 58 when the plunger-pin 52 is retracted, thereby relieving the pressure of the springs 54 upon the respective tension-disks. The rearward end of the plunger-pin 52 is laterally notched to receive one arm 59 of an elbow-lever fulcrumed upon the frame and having a lateral arm 60 adapted for engagement by the hooked upper 120 end of a pull-rod 61 secured upon the rearward end of the rock-lever 46, whereby the rocking of the lever 46 to lift the presser-foot causes the release of the tensions.

From the platform 8 rise the sockets 62 125 in which are adjustably secured by means of the set-screws 63 the posts 64 carrying the transverse bearing bosses 65. Slidingly journaled within the bosses 65 are the side bars 66 of the work-holder which are framed 130

together at opposite sides of the throat-plate by means of the cross-members 67 which are formed with apertured bosses 68 secured in position by means of set-screws 69.

The cross-members 67 are formed with upstanding lugs 70 upon which are secured by screws 71 the ends of the fabric-supporting and separating plates 72 which are forked at their adjacent ends to afford the spaced fabric-engaging members 73, those at the rearward edge of such plates being overhung by the tongues 74 spaced above the corresponding members 73. The members 73 nearest the front end of the machine are provided upon their lower and upper faces with the backwardly inclined impaling pins 75 and 76, and the corresponding members at the opposite edges of the supporting plates and their overhanging tongues are provided upon their lower and upper faces, respectively, with similar impaling pins 77 and 78.

In order to apply the ends of fabric to be united, the one is drawn laterally beneath the presser-foot and impaled upon the lower pins 75 and 77 at the ends of the section to be stitched, and the other is drawn laterally in the opposite direction beneath the presser-foot and impaled at corresponding points upon the upper pins 76 and 78, the fabrics thus being maintained taut in overlapping relation within the range of action of the stitch-forming mechanism, but having their adjacent faces separated by the supporting plates 72 and the overlying tongues 74.

The work-holder as thus described is adapted to be adjusted vertically to bring the fabrics as close as possible to the level of the face of the throat-plate by the means described, the throat-plate having in its face the transverse clearance grooves 28' to receive the points of the depending impaling pins. The cloth-plate 79 is similarly provided with transverse clearance grooves 79' for a like purpose.

The reduced forward end portion of the main shaft 33 has secured thereon the worm 80 meshing with the worm-wheel 81 whose tubular hub 82 is journaled upon the vertically disposed tubular stud 83 sustained at the forward side of the work-holder by a suitable extension 84 of the machine base 20. The worm-wheel 81 is formed in its upper face with a conical clutch-cavity and constitutes a driving clutch-member which is adapted for engagement by the depending clutch-disk 85 fitted within the same and depending from the pulley-wheel 86 formed with the peripheral belt-groove 87 and sleeved upon the worm-wheel hub 82. The clutch-member 85 is secured to the pulley 86 by means of screws 88 and is formed in its lower face

with an annular recess 89 in which are secured by screws 90 the arched lifting springs 91 adapted to rest upon the bottom of the clutch-cavity of the worm-wheel and to normally maintain the clutch-ring lifted out of clutching relation therewith.

The pulley-wheel 86 is embraced by a lateral crook in the belt 92 which passes over the guide-pulleys 93, 94 and 95 sustained by the machine frame beneath the cloth-plate 75 and intermediate the side bars 66; one end of such belt being apertured and entered by one member of a hook 96 whose other member enters an aperture in the forward cross-member 67, while the other apertured end of the belt is entered by a hook upon one end of the tension spring 97 having its eyed opposite end engaged by a pin 98 upon the depending lug 99 of a bar 100 carried by the other cross-member 67 of the work-holder.

The pulley 86 is surmounted by a washer 101 through which passes a thrust-pin 102 fitted within the bore of the stud 83 and having a head 103 which rests upon such washer and formed in its upper face with a cavity containing an anti-friction ball 104. Through the action of the springs 91 the ball 104 is normally maintained in contact with the upper margin of an inclined wear-plate 105 secured within a seat in the under face of a swinging arm 106 having its hub 107 fulcrumed upon the stud 108 which is sustained at the front end of the machine and beyond the stitch-forming mechanism 100 by means of the extension 84 of the bed 20. When the clutch-ring 85 is depressed into operative engagement with the worm-wheel 81 by engagement of the wear-plate 105 with the ball 104, the pulley 86 is caused to rotate with the worm-wheel and to act through the belt 92 to draw the work-holder in work-advancing direction and relatively to the stitch-forming mechanism.

The arm 106 is formed with a depending extension 109 having an aperture in which is inserted the hooked forward end of a rod formed in relatively adjustable sections 110 secured together by means of the clamp-block 111 and connected at its hooked opposite end with the apertured crank-arm 112 of a rocker fulcrumed upon the stud-pin 113 and provided with a lateral arm 114 connected by means of the similarly adjustable rod 115 with the apertured end of the lever 117 which is maintained normally retracted for disengagement of the driving and driven elements of the power-transmitter by means of the spring 117. A spring 116 connected at opposite ends respectively with the fulcrum-pin 113 and the clamp-block 111 maintains the arm 106 in normally retracted position.

The arm 106 constitutes one part of a compound lever of which the other part con-

sists of a forwardly extending arm 117 terminating in a forwardly and downwardly inclined handle 118, the arm 117 being flared and forked at its rearward end to 5 embrace a lug 106' upon the hub 107 upon which it is pivotally mounted by means of the cross-pin 119. The arm 117 is maintained normally raised by means of a spring 120 interposed between the bottom of a 10 socket in the lug 106' and a shoulder 121 afforded by the end of the fork in the arm 117. Upon the lug 106' is secured a stop-plate 122 carrying an adjustable stop-pin 123 adapted to rest upon the bottom of a 15 recess in the top of the arm 117 under the action of the spring 120 to yieldingly maintain the arm 117 in initial relation with the arm 106.

The arm 117 has a rearwardly and downwardly inclined extension 124 provided with a toe 125 extending beneath one end of a rock-lever 126 having the fixed fulcrum 127 intermediate its ends. The lever 126 is connected at its opposite end by means of the 25 hooked link 128 with an eyed lug upon the collar 129 which is fixed upon the pull-rod 130 with its hooked upper end entering an aperture in the presser-foot lifting rock-lever 46. The handle 118 is formed with 30 a longitudinal channel in its upper side to receive the latch-lever 131 which is pivotally mounted therein near the lower end by means of the cross-pin 132 and has at its opposite end an angular extension in the form 35 of a tooth 131' normally maintained slightly above the top of the arm 117 by means of the spring 133 interposed between the latch-lever and the bottom of a socket therefor in the handle 118.

40 The arm 117 works within a notch 134 in the depending lip upon the forward edge of the cloth-plate 79, the under side of such plate being formed with a notch 135 to receive the latch-tooth 131' which is pressed 45 upwardly by its spring to enable it to snap into the same when it comes into register therewith in the setting of the compound starting or controlling lever 106, 117, into operative or running position.

50 To the under side of the boss 68 of the work-holder cross-member 67 at the front side of the machine is adjustably secured by means of the clamp-screw 136 the longitudinally slotted shank 137 of a bent arm 138 55 sustaining a lateral tripping stud 139 which carries an anti-friction roller 140 having a range of movement with the work-holder embracing the normal position of the latch-lever 131.

60 The starting lever having been latched in running position to insure the operation of the stitch-forming mechanism and the travel of the work-holder for an indeterminate or unlimited period, the encounter of 65 the roller-stud 140 with the latch-lever 131

as the work-holder reaches a certain predetermined position effects the retraction of the latch-tooth from its holding notch 135 and thereby permits the starting lever to return to initial or starting position under 70 the action of the spring 116, whereby the stitch-forming mechanism and the work-holder actuating means are disconnected from the source of power and their operation is accordingly interrupted. 75

By a downward pressure upon the handle 118, the lever-arm 117, 124, is tilted upon the fulcrum-pin 119 and the toe 125 engages and rocks the lever 126 which effects the tilting of the lifting lever 46 and the simultaneous 80 raising of the presser-foot and the release of the tensions. As before indicated, the character of this lifting movement determines whether or not the presser-bar remains locked in raised position by means of 85 the cam-lever 48. It is obvious that in case the cam-lever 48 is swung over its fulcrum point in the lifting action, the presser-foot will remain lifted until a second lifting impulse is applied to the handle 118, when 90 the cam-lever may be again swung into releasing position.

The bracket-arm head 23 has secured at the back of its lower portion by means of a screw 141 a bearing bracket 142 to the side 95 of which is secured the depending arm 143 having the forwardly extending flange 144 to the bottom of which is fastened the forwardly extending guide-finger 145 having a forwardly and laterally inclined taper extension 146 extending partially across the line of seam. The inner edge of the finger 145 affords a ledger-blade for cooperation 100 with the lower cutting edge of a knife-blade 147 having upon its inner face intermediate 105 its ends the rigid fulcrum-stud 148 which is journaled within a bearing sleeve 149 in a depending boss of the bracket 142. The blade 147 carries at its rearward extremity 110 the lateral pin 150 entering the radial slot in a forked arm 151 having its hub 152 fitted 115 upon the tubular hub 153 of an upwardly extending operating lever 154 to which it is secured by means of a fastening screw 155 of an arm 155. 115

The hub 153 of the lever 154 is journeled upon the bearing sleeve 149 and has fitted upon its reduced upper portion 154' the sleeve 156 formed with an apertured lateral forked lug 157 embracing and pivotally connected by means of the pin 158 with a rigid arm 159 extending rearwardly from the hub of the needle-actuating crank-arm 31. In the rocking of the shaft 32, the arm 159 is given vibratory movements which are transmitted through the described pivotal and sliding connection to the operating lever 154 which thus imparts operative movement to the knife-blade 147, which is normally pressed against the finger 145 130

by means of the spring 160 interposed between the bottom of an axial socket of the fulcrum-stud 148 and the end of the screw-plug 161 entering the threaded outer end 5 of the bearing sleeve 149.

The hub 153 of the lever 154 has fitted thereon a collar 162 having an upwardly extending arm 163 secured adjustably thereon by means of the screw 164 entering an elongated aperture therein and having a lateral arm 165 to which is pivotally connected by means of the pin 166 the rocking foot 167.

The throat-plate 28 has at one side of its feed-dog apertures 168 a clearance aperture 169 having its bottom closed by means of a plate 170 secured to the suitably recessed under face of the throat-plate by means of screws 171 passing through slots 172 therein, whereby said plate is adapted for adjustment toward and from the line of seam. The plate 170 is shown formed upon its upper face with a lip 173 extending in the direction of feed and slightly inclined to the face of the throat-plate and laterally beveled to afford a cutting edge 173' at the face of said lip farthest from the stitch-forming mechanism to serve as a ledger-blade.

Cooperating with the ledger-blade 173 is a movable cutting blade afforded by the sharpened edge 174 of a smoothing finger 175 carried by a downwardly offset extension of a vibratory arm in the form of a holding plate or carrier 176. The blade-carrying portion of the plate 176 is overhung by the rocking foot 167 which is adapted to depress the same to impart cutting movements to the blade 174.

The plate 176 is secured to a lateral flange 177 of a sleeve 178 secured upon a fulcrum-pin 179 and having a depending arm 180 carrying the stop-screw 181. The pin 179 is journaled in spaced bearing lugs 182 of a rocker 183 which is in turn journaled upon the pivotal pin 184 mounted in the hanger 185 which is secured to the bottom of the throat-plate 28. The rocker 183 is provided with a socket 186 containing a pressure spring 187 interposed between an adjustable plug 188 and the end of a cap 189 slidably fitted within said socket and bearing upon the bottom of the holding plate 176. The spring 187 serves to normally maintain the cutting knife 174 in upper retracted position which is determined by the engagement of 55 the stop-screw 181 with an adjacent part of the rocker 183.

Suitably secured within the hanger 185 and passing freely through an aperture in the rocker 183 is a stud 190 having applied 60 to its threaded outer portion the nut 191 between which and said rocker is interposed a spring 192 yieldingly forcing the rocker toward the stitch line, and hence pressing the movable cutting blade 174 against the ledger-blade 173.

The lower ply *l* of fabric is introduced from the front end of the machine beneath the guide-finger 145 and intermediate the upper and lower blades 173 and 174 with the margin to be removed resting upon the 70 top of the throat-plate. The upper ply *m* of fabric is passed over the finger 145 and beneath the knife-blade 147 and thence intermediate the pressure member 167 and the arm-plate 176, it being understood that the 75 superposed plies are both introduced beneath the presser-foot and over the raised portion of the throat-plate beneath the same. As the work is advanced by the feeding mechanism, the marginal portions of the superposed plies of fabric respectively at opposite sides of the stitch-forming mechanism are removed close to the adjacent lines of seam.

It will be observed that both the upper and 85 lower ply cutters are actuated from the needle-actuating rock-shaft through a common operating lever 154, and that they are relatively adjustable in relation to the stitch-forming mechanism by means of the adjustment 90 provided in the plate 170 which sustains the lower ledger-blade against which the cooperating cutting blade is yieldingly pressed through the action of the spring 192.

Journaled upon the studs 193 in the lower 95 portions of the legs 1 of the end standards are the rock-bars 194 provided at opposite ends with crank-arms 195 each carrying a journal-pin 196 upon which is mounted a roller or caster 197. The arms 195 at the 100 front of the frame are provided with lateral ears 198 pivotally connected by bolts 199 with the ends of the toggle-links 200 which are pivoted together at their overlapped adjacent ends by means of the bolt 201. One 105 of such links adjacent their pivotal connection is formed with a forwardly extending tongue 202 passing over the top of the other link and affording not only a foot-piece for convenience of the operator in 110 straightening the toggle, but a stop for limiting the straightening movement of the toggle.

The toggle-links are so proportioned that when straightened the rollers 197 are thrust 115 apart and downwardly around the respective fulcrum-pins 193 as centers but not directly beneath the same, thereby lifting the stand to remove the ends of the legs 1 from the floor to facilitate movement of the machine from place to place. By raising the tongue 202 to bend the toggle, as represented in dotted lines in Fig. 1, the rollers 197 are permitted to move inwardly under the weight of the machine, thereby restoring 120 the table to normal position with its legs resting upon the floor.

While the present improvement is shown and described herein in its preferred embodiment, it will be evident that certain of 125

its features are adapted for use independently of the others and are susceptible of modification of construction and relative arrangement without departure from the invention.

Having thus set forth the nature of the invention, what I claim herein is:

1. In a sewing machine, in combination, stitch-forming mechanism, a work-holder 10 provided with impaling pins at opposite sides of the stitch-forming mechanism between which the fabric may be stretched, and means acting independently of the fabric for imparting to said work-holder a 15 continuous feeding movement during a plurality of consecutive stitch-forming cycles.
2. In a sewing machine, in combination, stitch-forming mechanism, a travelling work-holder, actuating means acting independently of the work for imparting to said work-holder a continuous feeding movement during a plurality of consecutive stitch-forming cycles, and a yielding connection 20 between coactive elements of said actuating means.
3. In a sewing machine, in combination, stitch-forming mechanism, a travelling work-holder, actuating means positively connected with the work-holder independently of the work and adapted to impart to the work-holder a continuous feeding movement during a plurality of consecutive stitch-forming cycles, and a yielding connection 25 between coactive elements of said actuating means.
4. In a sewing machine, in combination, stitch-forming mechanism, a travelling work-holder, and actuating means acting independently of the work and including 30 frictionally engaging driving and driven elements for yieldingly imparting to said work-holder a continuous feeding movement during a plurality of consecutive stitch-forming cycles.
5. In a sewing machine, in combination, stitch-forming mechanism, a travelling work-holder, and actuating means therefor including 35 a rotary shaft, a driving friction-clutch element having a worm-and-worm-wheel connection with said shaft, a driven friction-clutch element with means for establishing and interrupting its operative relation with the driving clutch-member, and a connection between said driven clutch-member 40 and the work-holder.
6. In a sewing machine, in combination, stitch-forming mechanism, a travelling work-holder, and actuating means therefor comprising a driven pulley-wheel and a belt 45 encircling the same and connected at opposite ends to said work-holder at points at opposite sides of said pulley-wheel.
7. In a sewing machine, in combination, stitch-forming mechanism, a travelling work-holder, and actuating means therefor

comprising a driven pulley-wheel and a belt encircling the same and connected at opposite ends to said work-holder at points at opposite sides of said pulley-wheel, a tension-spring being interposed in the connection between said work-holder and the belt to maintain the latter taut.

8. In a sewing machine, in combination, stitch-forming mechanism, a travelling work-holder, and actuating means therefor comprising a continuously driven actuator, a pulley-wheel operatively connected therewith by a friction clutch device, and a belt encircling said pulley-wheel and attached at opposite ends to said work-holder at 80 points at opposite sides of the pulley-wheel.

9. In a sewing machine, in combination, stitch-forming mechanism, a travelling work-holder, parallel guideways upon which said work-holder moves, and actuating 85 means for said work-holder comprising a driven pulley-wheel arranged at the same side of both of said guideways, and a belt encircling said pulley-wheel and attached at opposite ends to said work-holder midway of said guideways and at opposite sides of said pulley-wheel and directed to apply its pulling force in substantial parallelism with said guides.

10. In a sewing machine, in combination, 95 stitch-forming mechanism, a travelling work-holder, parallel guideways therefor, and work-holder actuating means comprising a driven pulley-wheel arranged at the same side of both of said guideways, a belt 100 encircling said pulley-wheel and attached at opposite ends to said work-holder midway of said guideways and at opposite sides of said pulley-wheel, and guide-pulleys engaging said belt at opposite sides of said 105 pulley-wheel for maintaining parallel with said guideways the portions of said belt attached to the work-holder.

11. In a sewing machine, in combination, a work-support, a travelling work-holder 110 sustained above the same and comprising a frame embracing the range of action of the stitch-forming mechanism and adapted to carry the fabric to be stitched, actuating means acting independently of the work for imparting to the work-holder work-advancing movements, and work-feeding means directly engaging the fabric adjacent the 115 stitch-forming mechanism.

12. In a sewing machine, in combination, 120 a work-support, a travelling work-holder sustained above the same and comprising a frame embracing the range of action of the stitch-forming mechanism and adapted to carry the fabric to be stitched, actuating 125 means acting independently of the work for imparting to the work-holder continuous work-advancing movements, and work-feeding means directly engaging the fabric adjacent the 130 stitch-forming mechanism and

comprising a work-engaging element performing reciprocatory work-advancing movements for each stitch-forming cycle.

13. In a sewing machine, in combination, 5 a frame comprising a bed-plate and a bracket-arm constructed with a standard and an overhanging member, stitch-forming mechanism disposed at the free end of said overhanging member, feeding mechanism 10 for imparting to the work feeding movements transversely of said overhanging member, driving means, a power-transmitter for establishing operative connection between said driving means and the stitch-forming 15 mechanism, and a starting lever for controlling said power-transmitter disposed beyond the end of the overhanging member of the bracket-arm remote from said standard.

20 14. In a sewing machine, in combination, a rotary shaft, stitch-forming mechanism connected therewith, a traveling work-holder, means adapted to impart to the same travelling movements and including a driving 25 element having a throw in and out driving connection with said shaft, and a starting lever for throwing the same into action, and means including an element carried by said work-holder for retracting said lever 30 to interrupt the travel of the work-holder.

15. In a sewing machine, in combination, a rotary shaft, stitch-forming mechanism connected therewith, a travelling work-holder, means adapted to impart to the same 35 travelling movements and including a driving element having a throw in and out driving connection with said shaft, and a starting lever for throwing the same into action, and means including an element adjustably 40 mounted upon said work-holder for causing retraction of said lever to interrupt the travel of the work-holder.

16. In a sewing machine, in combination, 45 a rotary shaft, stitch-forming mechanism connected therewith, a travelling work-holder, means adapted to impart to the same travelling movements and including a driving element having a throw in and out driving connection with said shaft, and a spring- 50 retracted starting lever for throwing the same into action, a spring-catch for maintaining the starting lever in operative position in opposition to its spring, and a tripping element partaking of the movements 55 of said work-holder for tripping said spring-catch and permitting the lever to assume initial position under the action of its spring.

17. In a sewing machine, in combination, 60 stitch-forming mechanism, a work-holder, actuating means for imparting thereto travelling movements, controlling means for said mechanism and said actuating means, and means including a common lever having 65 positive connection with each controlling

means whereby operation thereof will establish and interrupt operative relation between the stitch-forming mechanism and work-holder actuating means and their respective sources of power.

18. In a sewing machine, in combination, 70 a rotary shaft, stitch-forming mechanism connected therewith, a traveling work-holder, actuating means adapted to impart to the same travelling movements and including a driving element having a disconnectible driving connection with said shaft, a power-transmitter for establishing and interrupting operative relation between said shaft and the source of power, and a lever 75 having independent connections with said power-transmitter and said driving element for simultaneously throwing into and out of operation the stitch-forming mechanism and work-holder actuating means.

19. In a sewing machine, in combination, 80 stitch-forming mechanism, a presser-foot, lifting means therefor, a travelling work-holder, actuating means for imparting thereto travelling movements, and means 85 including a common element for establishing and interrupting operative relation between the stitch-forming mechanism and work-holder actuating means and their respective sources of power and for operating 90 the presser-foot lifting means.

20. In a sewing machine, in combination, 95 a rotary shaft, stitch-forming mechanism connected therewith, a presser-foot, lifting means therefor, a travelling work-holder, actuating means adapted to impart to the same travelling movements and including a driving element having a disconnectible driving connection with said shaft, a power-transmitter for establishing and interrupting 100 operative relation between said shaft and the source of power, and a lever having independent connections with said power-transmitter, with said driving element, and with said presser-foot lifting means, for 105 throwing into and out of operation the stitch-forming and work-holder actuating means and operating said presser-foot lifting means.

21. In a sewing machine, in combination, 110 stitch-forming mechanism, driving means therefor including a clutch, a presser-foot, lifting means therefor, a lever, operative connections from said lever to said clutch and said presser-foot lifting means whereby 115 the stitch-forming mechanism may be thrown into and out of action and the presser-foot raised and lowered, respectively, and detaining means adapted to maintain the presser-foot lifted independently of the position of said lever after actuation.

In testimony whereof, I have signed my name to this specification.

ALBERT H. DE VOE.
